UNITED STATES PATENT OFFICE.

HENRY HACKMAN, JR., OF PAQUE, PENNSYLVANIA.

DOOR-LATCH.

Specification of Letters Patent No. 22,234, dated December 7, 1858.

To all whom it may concern:

Be it known that I, HENRY HACKMAN, Jr., of Paque, in the county of Lancaster and State of Pennsylvania, have invented a new and Improved Push-and-Pull Door Latch or Fastener; and I do hereby declare that the following is a full and clear description of the same, reference being had to the annexed drawings, making a part of this specification, in which—

Figure 1 is a perspective view of the interior of the latch; Fig. 2, the revolving latch-bolt, with the levers G, G, peg I and spiral spring K; Fig. 3, the knobbed and shoulered shank or push and pull handle; Figs. 4 and 5, two forms of spring catches, to hold the door closed; Fig. 6, the latch and catch in place.

Its construction and operation is simple. The frame or latch box D, D, C made as usual, having a partition piece B, dividing the interior into a lesser and a greater chamber. The pivot N, of the bolt E, Figs. 1 and 2, enters the side A of the frame, supported in the partition B and projects with its notched end H, to the spring catch O on the door. Frame-plate S, Figs. 4, 5 and 6, through the front side C, of the latch-frame. On the bolt E, are two upright levers G, G, the external one having a peg I, resting on the end of a coiled spring K fastened by a screw N, or otherwise in the upper inside corner of the endpiece A of the latch frame. The knobbed shank L, has a shoulder m, which is in contact with the lever arms G, G, the narrower portion V of the shank lying closely between the arms G, G, at a distance

above the bolt E, the spring K, holding the lever arms close against the shoulder m, so that a simple pull from one side or a push against the knob on the other side inclines the lever arms G, G, which being firmly fixed to the bolt E, causes it to revolve in the direction of the bent arrows Figs. 4, 5, and 6, pressing with its notched end H, on the spring catch O, (either hinged as at R, Fig. 5, or as shown in Figs. 4-6,) thereby depressing it so as to allow the rounded bolt to pass over it. The check catch t, Figs. 4-6 prevents the spring from rising higher than is necessary.

P is the support for the spring catch O, Fig. 4. The hinged catch has a spring Q beneath it Fig. 5.

The shoulder m, on the shank L is rounded beneath, so as to adapt it to the inclination of the lever arms when operated on.

Ordinary key locks may be used in connection with them, and the several parts so made as to be used either for right or left doors, and are deemed superior to weights for keeping the doors firmly closed, where a push and pull door is desired.

What I claim as my invention, and desire to secure by Letters Patent is—

The revolving bolt E, the lever arms G, G, peg I coiled spring K, the shoulered shank L, and spring catch O, when combined and used substantially as herein described.

HENRY HACKMAN, Jr.
